Frank Warren,

UNITED STATES PATENT OFFICE.

JOHN C. CORBIN, OF SEATTLE, WASHINGTON.

CONDENSER.

1,397,621.

Specification of Letters Patent. Patented Nov. 22, 1921.

Application filed May 4, 1920. Serial No. 378,862.

To all whom it may concern:

Be it known that I, JOHN C. CORBIN, a citizen of the United States, residing at Seattle, in the county of King and State of Washington, have invented a certain new and useful Improvement in Condensers, of which the following is a specification.

My invention relates to improvements in condensers for refrigerating apparatus and 10 the object of my invention is to provide a condenser embodying an oil intercepting chamber that is adapted to be disposed within the condenser and is arranged to be submerged in the cooling water circulating 15 through the condenser.

Another object is to provide a condenser embodying an oil intercepting chamber through which the gas to be condensed and purified is adapted to pass and wherein the 20 particles of oil carried in suspension in the said gas are intercepted or separated therefrom during the purifying and preliminary condensation process.

A further object is to provide a condenser 25 embodying an oil intercepting chamber which is adapted to further increase the capacity of the condenser thereby accelerating the condensation of the gases that pass therethrough and to also expedite the separating the oil particles carried by the said 30 gases.

A still further object is to provide a condenser embodying an oil intercepting chamber that is readily adaptable to be assembled with the compressor unit of the refrigerating apparatus.

A still further object is to provide a condenser of the counter flow type that embodies a submerged oil intercepting chamber 40 wherein the initial cooling water is directed to strike or impinge the coils containing the coldest gases therein.

A still further object is to provide a condenser embodying an oil intercepting chamber 45 which combines strength and durability with economy of weight, that embodies simplicity and efficiency in its plan of construction, that is positive in its operation and that will not readily get out of order.

With the above and other objects in view 50 which will appear as the description proceeds, my invention resides in the novel construction, combination, adaptation and arrangement of parts hereafter described 55 and claimed.

I accomplish these objects by devices

illustrated in the accompanying drawings, wherein—

Figure 1 is a view partly in medial vertical section and partly in elevation of a condenser embodying my invention;

Fig. 2 is a view in top plan of the same; and

Figs. 3 and 4 are views in horizontal section taken on broken lines 3, 3 and 4, 4, respectively, of Fig. 1.

Referring to the drawings, throughout which like reference numerals indicate like parts, the numeral 10 designates the outer cylindrical shell or casing of my condenser 70 having a bottom wall 11 which may be integral or otherwise fixedly secured to the lower end of the casing 10 which casing is further provided on its upper end with an outwardly projecting annular flange 12. 75

A crowned plate or cover 13 constitutes the closure for the upper open end of the casing 10, the cover 13 having an outwardly projecting annular or peripheral flange 14 that is adapted to abut when positioned the 80 annular flange 12 and being fixedly secured thereto by cap screws or studs 15.

Concentrically disposed and threadably engaged in the bottom wall 11 of the casing 10 is the upper end of an intake pipe 16 85 which serves as a conduit for the cooling water for the condenser and also serves as a support for the same.

Threadably engaged on the lower end of said intake pipe 16 is a reducing T 17 which 90 is connected at its lower end by a threaded plugged nipple 18 to a base plate or floor flange 19. The reducing branch 20 of the T 17 being adapted to threadably receive and engage the outlet end of a supply pipe 95 21, which forms the conduit for the cooling water for the condenser.

To secure proper and uniform circulation through the condenser I provide an outlet or overflow pipe 22 which is concentrically disposed and threadably engaged on its lower end in a central boss 23 formed on the upper side of the crowned plate 13. The upper end of the outlet pipe 22 may, if desired, be connected to the water jacket of 100 the compressor unit, not shown, of the refrigerating apparatus for the purpose of further utilizing the cooling water as a cooling medium for the compressor, thereby 105 economizing in the amount or quantity of 110 cooling water necessary for the proper functioning of the refrigerating apparatus.

Disposed concentrically within the outer cylindrical casing 10 is an inner cylindrical casing 24 which forms the oil intercepting chamber 25 which casing 24 is somewhat 5 smaller in diameter and shorter in length than the outer casing 10 and is adapted to be submerged at all times in the cooling water circulating within the outer casing 10 thereby providing the maximum surface area for 10 the cooling action of the cooling water.

The inner casing 24 is provided on its lower end with a bottom wall 26 and on its upper end with a top wall 27, which walls are integral with or otherwise fixedly secured to the cylindrical walls of said casing. 15

The lower or bottom wall 26 is disposed in spaced apart relation with respect to the lower or bottom wall 11 of the casing 10 by a distance piece or hollow pedestal 28 which 20 serves as a support for the casing 24 within the casing 10.

The upper or top wall 27 of the casing 24 is suitably spaced from the inner wall of the cover 13 of the casing 10, as shown in Fig. 1, 25 and is provided on its inner face with an inwardly and downwardly projecting inlet conduit 29, which may be integral with or otherwise fixedly secured therein, through which the gases to be condensed are conducted, the pipe 29 extending downwardly within the chamber 25 to a point far enough to expedite and positively insure the precipitation and trapping of the entrained oil carried by the gases thereby preventing the entrained oil from rising with and being carried off by the gases during the circulation of the 30 same through the condenser.

Formed on the upper face of the upper or top wall 27 is a threaded nipple 30 which 40 may be integral or otherwise fixedly secured to said wall, the nipple 30 being disposed in axial alignment and arranged to communicate with the conduit pipe 29 as shown more clearly in Fig. 1.

Threadably engaged on the nipple 30 is one 45 end of an elbow 31, the other end of which is adapted to receive the outlet end of the pipe 32 through which the gases from the compressor unit, not shown, are conducted to the chamber 25. The pipe 32 is arranged to extend outwardly through the cylindrical wall of the casing 10 at a point adjacent its upper end, the casing 10 being provided with a stuffing box 33, of any well known form, 50 where the pipe 32 passes through the casing.

To automatically control the supply of cooling water to the condenser I utilize the inlet pressure of the gases passing through the pipe 32 to the chamber 25 to actuate an 60 automatically controlled diaphragm valve 35, of any well known form, which is adapted to be interposed in the cooling water supply pipe 21. The valve 35 is connected by a pipe 36 with the pipe 32 thereby permitting the pressure of the gases in the pipe 65

32 to actuate the metallic diaphragm disposed within the valve 35.

It will be obvious from the foregoing that should the pressure of the gases in the pipe 32 increase from any cause, the increased 70 pressure will act on the metallic diaphragm of the valve 35 to further open the valve thereby providing an increased volume of water to counteract the increased pressure of the gases. However, should the pressure of 75 the gases in the pipe 32 decrease from any cause, the spring 37 on the valve 35 will tend to close the latter against the decreased pressure of the gases acting on the upper side of the diaphragm disposed within the valve 35, 80 thereby regulating and controlling the supply of cooling water in direct proportion to the pressure of the gases in the pipe 32.

The upper wall 27 of the casing 25 is further provided with an outlet opening or aperture 40 which permits of the egress of the gases from the chamber 25 and which also furnishes communication between the chamber and a helical condensing coil 41, which coil is adapted to be concentrically 90 disposed within the outer casing 10 and around the inner casing 24 in the annular space formed by the cylindrical walls of the aforesaid casings and is further adapted to be at all times submerged in the cooling 95 water circulating within the casing 10 as shown more clearly in Fig. 1.

The upper end 42 of the coil 41 is bent and inwardly directed toward the center of the coil as shown in Fig. 3 and is adapted to be threadably engaged in the upper outer end of an elbow 43, the other or lower end of the elbow 43 being provided with a flange 49 which is adapted to be fixedly secured, as by cap screws 45, to the outer face of the 100 upper wall 27. The elbow 43 is adapted to communicate and register with the aperture 40 in the upper wall 27 as shown more clearly in Fig. 1.

The lower end 46 of the coil 41 is adapted to threadably engage the upper and enlarged end of a downwardly directed reducing elbow 47, the elbow being adapted to threadably receive in its lower and smaller end the upper end of a downwardly projecting pipe 110 48, which pipe is adapted to project downwardly and outwardly through the bottom wall 11 of the casing 10, the wall 11 being provided with a stuffing box 49, of any well known form, at the point where the pipe 48 passes through the wall 11 as shown in Fig. 1; and is further provided on its lower outer end with an elbow 50 which in turn is adapted to threadably engage and receive the inner end of a pipe 51, the outer end of the 115 pipe being adapted to connect and communicate with a liquid storage chamber, not shown.

It will be obvious by referring to Fig. 1 that the coil 41 is retained or maintained 120

in its normal fixed position by its threaded connection with the elbow 43 on its upper end and by a similar connection with the reducing elbow 47 on its lower end.

5 In order to drain the accumulated intercepted oil from the chamber 25 I have provided a pipe 55 the upper end of which is threadably engaged in the lower or bottom wall 26 of the casing 24, the pipe 55 being disposed within and projecting downwardly through the distance piece or pedestal 28 and being further adapted to project downwardly and outwardly through the bottom wall 11 of the casing 10, the wall 11 being provided with a stuffing box 56 where the pipe 55 passes through the same.

Threadably engaged on the outer lower end of the pipe 55 is an elbow 57 having a nipple 58 threadably engaged on its outer end, the nipple 58 being adapted to threadably engage the inlet end of a shut-off valve 59, the outlet end 60 of which being directed downwardly to facilitate the draining of the oil from the chamber 25.

25 The inner casing 24 is retained and maintained in its normal fixed position on its pedestal 28, by the pipe 55 and the elbows 31 and 43 as will be readily understood.

It will be obvious that when a condenser 30 fabricated in accordance with my invention is used in conjunction or embodied with marine refrigerating apparatus or installations on board ships or vessels, where it is necessary and essential from the standpoint 35 of economy to use sea water as the cooling medium for the condenser, that in order to avoid the corrosive action of the sea water on the interior walls of said condenser, that it is important and advisable to treat the 40 said walls with a non-corrosive substance.

I have therefore found in practice and after exhaustive tests that the maximum and desired results are obtained from the condenser when the interior walls of the same 45 are tinned, thus providing an economical and efficient means to resist the corrosive action of the sea water circulating upwardly through the said condenser.

In the operation of my condenser the 50 gases to be condensed or liquefied are delivered under pressure through the pipe 32 and the pipe 29 and are discharged into the chamber 25 at the lower end of the pipe 29 where they are relieved of the entrained 55 oil by impinging or contacting with the cooled inner surfaces of the cylindrical walls of the chamber 25, the entrained oil by reason of its greater specific gravity due to its cooled condition is precipitated to the bottom 60 of the chamber where it is drawn off through the drain pipe 55 and valve 59 when desired. The purified gases pass through the opening 40 into the coil 41 where they are cooled and condensed to a 65 liquid state by the cooling water circulat-

ing within the casing 10. The liquefied gases are then conducted through the pipes 48 and 51 to a liquid storage chamber, not shown. Should any fluctuations of pressure of the gases occur within the chamber 25 and the pipe 32 the automatic control valve 35 actuated by the fluctuating pressure will operate to provide a sufficient flow of cooling water to offset the fluctuation as hereinbefore described.

70 From the foregoing description taken in connection with the accompanying drawings, the advantages of the construction and of the method of operation will be readily apparent to those skilled in the art to which the invention pertains, and while I have described the principle of operation of the invention, together with the device which I now consider to be the best embodiment thereof, I desire to have it understood that 80 the device shown is merely illustrative and that such changes may be made when desired as are within the scope of the following claims:

What I claim is:

90 1. The combination with a condenser, of an oil intercepting chamber adapted to be normally submerged in the cooling medium circulating through said condenser, said chamber having suitable opening for the ingress and egress of the gases to be purified and condensed, means for draining the intercepted oil from said chamber, and means actuated by the pressure of said gases adapted to automatically control the flow of said 100 cooling medium.

2. The combination with a condenser, of an oil intercepting chamber adapted to be normally submerged in the cooling medium circulating through said condenser, said chamber having inlet and outlet openings formed in the upper portion thereof for the ingress and egress of the gases to be purified and condensed, a downwardly and inwardly projecting conduit within said chamber 110 adapted to register with said inlet opening, means disposed in the lower portion of said chamber for draining the same, and means actuated by the pressure of said gases adapted to automatically control the flow of said 115 cooling medium.

3. In a condenser comprising an outer casing having inlet and outlet openings, an inner casing forming an oil intercepting chamber concentrically disposed within said outer casing, a gas inlet pipe adapted to conduct gases under pressure into said oil intercepting chamber, a condensing coil concentrically disposed around said inner casing having its upper end adapted to communicate with the upper end of said oil intercepting chamber and its lower end adapted to communicate with a liquid storage chamber, draining means disposed in the lower portion of said oil intercepting chamber.

ber, and means for controlling the flow of the cooling medium of the condenser and adapted to be actuated by the pressure of the gases in said gas inlet pipe.

- 5 4. In a condenser comprising an outer casing, a cover therefor, an inlet supply pipe disposed in the lower portion of said casing, an outlet pipe disposed in said cover, an inner casing forming an oil intercepting 10 chamber concentrically disposed within said outer casing, a downwardly and inwardly projecting conduit disposed within said chamber, a gas inlet pipe adapted to conduct gases under pressure through the said 15 conduit into said chamber, a condensing coil

concentrically disposed around said inner casing having its upper end adapted for communication with the upper end of said oil intercepting chamber and its lower end adapted to communicate with a liquid storage chamber, draining means disposed in the lower portion of said oil intercepting chamber, and means to control the flow of said cooling liquid adapted to be actuated by the pressure of the gases within said gas 20 inlet pipe.

In witness whereof, I hereunto subscribe my name this 28th day of April, A. D. 1920.

JOHN C. CORBIN.
